(57) **CLAIM**

The ornamental design for a jewel-bedecked cylindrical floss dispenser, as shown and described.

DESCRIPTION

FIG. 1 is a perspective view of the jewel bedecked, cylindrical floss dispenser with the top closed.

FIG. 2 is a perspective view of the jewel bedecked, cylindrical floss dispenser with the top open, and showing a thread of floss exiting from the opening.

FIG. 3 is a right side view of the jewel bedecked, cylindrical floss dispenser with the top closed.

FIG. 4 is a front view of the jewel bedecked, cylindrical floss dispenser.

FIG. 5 is a front view of the jewel bedecked, cylindrical floss dispenser with the top open and showing exiting floss.

FIG. 6 is a right side view of the jewel bedecked, cylindrical floss dispenser with the top open and showing exiting floss.

FIG. 7 is a rear view of the jewel-bedecked, cylindrical floss dispenser with the top closed.

FIG. 8 is a top view of the jewel bedecked, cylindrical floss dispenser with the top closed.

FIG. 9 is a bottom view of the jewel bedecked, cylindrical floss dispenser; and,

FIG. 10 is a top view of the jewel bedecked, cylindrical floss dispenser, with the top open and showing exiting floss.

The broken lines in the drawings are for illustrative purposes only and form no part of the claimed design.
